(57) **CLAIM**

We claim the ornamental design for the instrument connector, as shown and described.

DESCRIPTION

FIG. 1 is a perspective view from the top of an instrument connector showing our new design;

FIG. 2 is a perspective view thereof, as viewed from the bottom.

FIG. 3 is a front elevation view.

FIG. 4 is a plan view of the bottom.

FIG. 5 is a plan view of the top.

FIG. 6 is an elevation view of the right side; the left side thereof being the same.

FIG. 7 is a perspective view from the top of an instrument connector showing a second embodiment of our new design; FIG. 8 is a perspective view, as viewed from the bottom, of the second embodiment of our new design;

FIG. 9 is a front elevation view of the second embodiment. FIG. 10 is a plan view of the bottom of the second embodiment;

FIG. 11 is a plan view of the top of the second embodiment; and,

FIG. 12 is an elevation view of the right side of the second embodiment; the left side thereof being the same.

The broken lines showing the gripping portion, the strain reliever and cord are included for the purpose of illustrating portions of the connector that form no part of the claimed design.
